APPARATUS FOR EVALUATING THE RATE OF CHANGE OF A MAGNITUDE

Geoffrey Huson Stephenson, London, and Richard Herbert Booth, Buckinghamshire, England, assignors to Electric & Musical Industries Limited, Hayes, England, a British company

Application April 17, 1952, Serial No. 282,854

Claims priority, application Great Britain April 18, 1951

5 Claims. (Cl. 235—61)

This invention relates to potentiometers, and especially but not exclusively to apparatus employing potentiometers for evaluating the rate of change of a variable.

In the specification of United States application Serial No. 207,490 there is described apparatus for evaluating a smoothed rate of change of a variable (say displacement) whose instantaneous value is observed at discrete times. As described in the aforesaid application, and as will hereinafter appear, the smoothing reduces to a minimum the mean square deviation between the observed values of the variable (which values are subject to random errors) and the corresponding set of values represented by the smoothed rate. The smoothing is sometimes referred to as applying a weighting function since the effect of the smoothing is to weigh the evaluation of the rate more in favor of some of the values of the variable than of others. The apparatus described in the aforesaid specification involves the employment of a tightly coupled inductive potentiometer having sliding contacts which cyclically traverse the potentiometer and the apparatus has the desirable property that observations made outside a predetermined interval referred to as the weighting period play no part in the rate evaluation, so that "stale" observations do not enter into the evaluation. However, the structure of a potentiometer such as described above has been associated with certain difficulties and the main object of the present invention is to reduce such difficulties.

According to the present invention there is provided a potentiometer comprising an array of impedance sections, a switch between each section of said array and the next section thereof and between the last section of said array and the first section thereof, each switch being arranged when closed to connect adjacent sections, means for feeding electrical signals to fixed points in the respective sections, and means for operating said switches in a cyclic order to connect a cyclically changing plurality of said sections in a series chain, said cyclic order being predetermined to produce the effect of displacing the feed points in succession along the chain. This effect is produced by operating the switches so as to incorporate the impedance sections in succession in the chain at one end and to discard them subsequently from the chain at the other end. As each new section is incorporated in the chain, the previously incorporated sections and with them the corresponding feed points are in effect displaced towards the end of the chain from which they are eventually discarded, this process being repeated in each cycle.

According to one application of the present invention there is provided apparatus for evaluating the rate of change of a first variable, say displacement, with respect to a second variable, say time, comprising an array of inductances magnetically coupled one to another, a switch between each inductance of said array and the next inductance thereof and between the last inductance of said array and the first inductance thereof, each switch when closed being arranged to connect the adjacent inductances,

2

a plurality of impedances one leading to a fixed point on each inductance, means for operating said switches in a cyclic order to connect a cyclically changing plurality of said inductances in a series chain, the cyclic order being predetermined to produce the effect of displacing said fixed points in succession along said chain, and means for applying to said impedances alternating voltages having amplitudes representative of values of the first variable corresponding to values of the second variable represented by said fixed points, the impedance and mutual coupling of said inductances being such that the potential gradient set up along the chain is representative of a smoothed rate of change of the first variable with respect to the second variable. By the potential gradient along the chain is meant the variation in amplitude of the alternating voltage set up between the ends of the chain, the mutual coupling between the inductances being arranged so that the amplitude varies substantially linearly along the chain.

20 In this application of the invention, means are preferably provided for modifying the cyclic operation of said switches so as to reduce the number of inductances maintained in the series chain. This provision enables the interval over which the smoothed rate is evaluated to be reduced when the evaluated rate is changing rapidly and is thus more susceptible to error in evaluation, and means may be provided, responsive to variations in the evaluated rate of change or of a magnitude dependent thereon for rendering the means for modifying the cyclic operation of the switches automatically effective when the rate of variation exceeds a predetermined value.

In order that the said invention may be clearly understood and readily carried into effect, the same will now be more fully described with reference to the accompanying drawings.

35 Figure 1 illustrates diagrammatically one form of apparatus in accordance with the present invention, and Figure 2 illustrates mechanism for operating switches in the apparatus of Figure 1.

40 Referring to the drawing, it will be assumed that there is an interval τ between successive observations of the variable (say x) and that the time rate of change of this magnitude is to be evaluated. The apparatus illustrated is arranged to operate with a maximum weighting period of 9τ , that is, the observations of x taken into account in the rate evaluation cover an interval which does not exceed 9τ . The total weighting period of one cycle of operations is divided into twenty equal intervals, the starts of which are denoted at times 0, 1, 2 . . . 19, the observations of x being made at the times 1, 3, 5 . . . 19 on this time scale.

45 The apparatus comprises an array of ten tightly coupled inductive sections $L_1, L_2 \dots L_{10}$, only four of the sections being shown in the drawing for convenience of illustration. The sections are arranged to have a very high shunt impedance and are not tied to any reference potential. Switches $A_1, A_2 \dots A_{10}$ are interposed as shown between each section of the array and the next section and between the last section and the first section of the array. Moreover, feed resistances $R_1, R_2 \dots R_{10}$ are provided as shown for feeding signals representative of discrete values of x to one end of the sections $L_1, L_2 \dots L_{10}$ from temporary stores which are indicated merely in block form and denoted respectively by the references $S_1, S_2 \dots S_{10}$. The construction of the temporary stores S_1 to S_{10} forms no part of the present invention and a suitable construction of store is described, for example, in the specification of United States application Serial No. 208,297. For the purposes of the present application, it is sufficient to regard each store as a transformer having a primary winding which is energised by an alternating voltage of fixed amplitude and phase

and having a secondary winding the number of turns of which can be varied by the operation of a series of relays to cause the voltage set up across the secondary winding to be the analogue of an observed value of x , thereby "filling" the store. During each cycle of operation, the stores S are filled at the times represented by the numbers in the lower row above the stores, the stores having been previously cleared of older information at the times indicated in the upper row of numbers. The voltage analogue fed to a store at a specified time is of course representative of the instantaneous value of x at that time. Moreover, the switches $A_1 \dots A_{10}$ are opened and closed in a cyclic manner at the times denoted by the numbers below the switches. An output signal representative of the smoothed rate ($\dot{x}$) is obtained from a secondary winding L inductively coupled to the sections $L_1 \dots L_{10}$.

In describing the operation of the apparatus illustrated in Figure 1 it will be assumed that a time just before the end of a cycle of operations has been reached, that is a time just before time 0. At that time all the switches except the switch A_1 are closed and the stores $S_1 \dots S_{10}$ are filled with information representative of the values of x at the times corresponding to a time denoted in the lower row of numbers above the stores. The sections $L_1 \dots L_{10}$ then constitute a single tightly coupled inductive potentiometer having applied to equi-spaced points thereon signals representative of observations of x at discrete equi-spaced time intervals and a signal representative of the smoothed rate $\dot{x}$ is obtained from the secondary winding L as explained hereinafter. At time 0 switch A_2 is opened and the store S_1 is cleared while at time 1 the switch A_1 is closed and the store S_1 is filled with information representative of the latest value of x , i. e. the value at time 1. Thereafter until time 2 the sections $L_2 \dots L_{10}$, L_1 function as a single potentiometer and in effect the potentiometer has been displaced by one section with reference to the points at which are applied the information representative of the values of x . This process is continued as long as rate measuring is taking place, a cycle of operations being completed in a period of 10τ . A smoothed value of x is therefore obtained from the secondary winding L and observations made outside the weighting period of 9τ have no effect in the evaluation. Each change in the sections which are connected in series to form the tightly coupled potentiometer has the effect of discarding the "oldest" value of x in favor of a value of x which has just been observed. The evaluated smoothed rate is therefore always based on the most recently observed values of x .

The theoretical basis of the invention will be illustrated for the case in which the switches are in the states shown in Figure 1. It will, of course, be appreciated that the following discussion is applicable to any state of the switches $A_1 \dots A_{10}$, with appropriate changes in the notation. Referring to Figure 1, assume that the alternating voltages in the stores $S_1 \dots S_{10}$ have amplitudes $x_0, x_1 \dots x_9$ respectively, these amplitudes being representative of successive observations of x at the times 1, 3, 5, 7, 9, 11, 13, 15, 17, 19. Let $a, a+v, a+2v \dots a+9v$ be a set of smoothed voltage amplitudes having an arbitrary constant rate of change. The deviation between any value of x say x_r , and the corresponding smoothed value $a+rv$ is $x_r - a - rv$. The criterion for minimum mean square deviation between the values $x_0, x_1 \dots x_9$ and the values $a, a+v \dots a+9v$ is that

$$\sum_{r=0}^9 \delta_r^2 \equiv \sum_{r=0}^9 (x_r - a - rv)^2$$

should be a minimum. Differentiating partially with respect to a and v gives

$$\sum_{r=0}^9 (x_r - a - rv) = 0$$

$$\sum_{r=0}^9 r(x_r - a - rv) = 0$$

Therefore the criterion for minimum mean square deviation is

$$\sum_{r=0}^9 \delta_r = 0$$

$$\sum_{r=0}^9 r \delta_r = 0$$

In the arrangement shown in Figure 1, the mutual coupling between the inductive sections $L_2 \dots L_{10}$ is such that the voltage amplitudes at the junction of the sections can be represented by the set of values $a, a+v, a+2v$. Let i_0 be the current through the resistor R_1 , let i_1 be the current through the resistor R_2 , and so on. In that case,

$$\delta = i_r R$$

where each of the resistors $R_1, R_2 \dots R_{10}$ has the value R . The currents in the sections of the potentiometer formed by sections $L_2 \dots L_{10}$ are as indicated, there being of course no current in the section L_1 . Since this potentiometer is not tied to any reference potential, it is apparent that

$$i_0 = - \sum_{r=1}^9 i_r$$

30 Hence

$$\sum_{r=0}^9 \delta_r = 0$$

The first condition for minimum mean square deviation is therefore satisfied. Moreover, if the output current of the arrangement is zero or, in other words, if the ampere turns of a potentiometer formed by the sections $L_2 \dots L_{10}$ are zero, then

$$\sum_{r=0}^9 r \delta_r = 0$$

This follows from the fact that i_9 flows through nine sections, i_8 flows through eight sections, and so on. This is the second condition for minimum mean square deviation and, although in practice it is not possible to arrange that the ampere turns of the potentiometer are exactly zero, the condition is sufficiently approached for practical purposes by arranging that the sections $L_1 \dots L_{10}$ have, as aforesaid, a very high shunt impedance. The potential gradient set up along the potentiometer formed by the interconnected sections is, therefore, within the limits of practical error, representative of the desired smoothed rate of change of x .

In the operating mechanism for the switches A_1, A_2 which is illustrated in Figure 2, numbered terminals are shown and it is to be understood that the numbers denote the times in a cycle of operation at which these terminals are earthed. Normally, that is when not earthed, each of the terminals is biased to a D. C. level of +18 volts and earthing is effected at the appropriate times by means of a suitable rotary selector switch which maintains each terminal in its turn at earth potential for a period, for example, of 100 milliseconds. In Figure 2 the operating mechanisms of only two switches namely A_1 , and A_2 are illustrated, and corresponding parts of the two mechanisms are denoted by the same reference letters but differentiated by the suffixes 1 and 2. The operating mechanisms for all the switches are in fact identical apart from the times when the terminals are earthed, which times in the case of the mechanisms not shown can be derived by cyclic permutation on the basis of the timings indicated in Figure 1. Only the operating mechanism for the switch A_1 will be described, it comprises a main relay winding B_1 connected in series with a rectifier C_1 between terminals earthed respectively at times 1 and 7. The

winding B_1 when energised closes a holding switch D_1 which when closed connects the junction of B_1 and C_1 to an earth line E . The winding B_1 when energised also closes a control switch F_1 for an auxiliary relay winding G_1 , thereby closing a current path through G_1 from a terminal earthed at time 18 to a second earth line H . When G_1 is energised it closes the switch A_1 and also another switch J_1 . When the latter switch is closed a resistance K_1 is connected as shown from the upper end of G_1 to one side of a two-way switch N and thence, depending on the state of the switch N either to the earth line H or to a bias source of +18 volts. Ganged master switches M_1 and M_2 are connected in the earth lines E and H respectively, the apparatus being conditioned for operation by closing the master switches. The switch N may be operated automatically by a relay P which is responsive to the output of an amplifier Q included in the feedback loop of a servo system, or alternatively the switch N may be manually operated. The input to the servo system is the present value of the magnitude x , and the output of the amplifier Q in addition to operating the relay P drives a servo motor U which operates a follow-up potentiometer V . This latter device has a negative feedback connection W from V to the input of the amplifier Q . It is arranged that in operation of the apparatus the switch N is normally maintained in the position indicated in full-lines, but if the output of the amplifier Q exceeds a certain small value the relay P is energised to change the state of switch N and connect the resistance K_1 to the 18 volts bias source.

Until it is desired to commence rate measurement, switches M_1 and M_2 are left open. When, with the switches M_1 and M_2 thus open, terminal 1 is earthed at time 1 relay winding B_1 is energised through the rectifier C_1 and the switches D_1 and F_1 are momentarily closed. As soon as the earthing pulses on the terminal 1 has ceased current ceases to flow in winding B_1 and switches D_1 and F_1 re-open. As switch M_2 is open no current flows through winding G_1 and switch A_1 is unaffected.

As soon as it is desired to commence rate measurement, switches M_1 and M_2 are closed. Suppose this is just before time 1. Thus when at time 1, terminal 1 is earthed winding B_1 is energised as before but now contacts D_1 can pass a holding current through the earth line E and switch M_1 thus keeping the winding B_1 in an energised condition in spite of the terminal 1 being returned to a positive potential of 18 volts. Closure of the switch F_1 energises the winding G_1 since current can now flow from the terminal 18 to the earth bar H , and the switches A_1 and J_1 become closed. Assuming the switch N is in its normal state as indicated in full lines, closure of the switch J_1 connects the upper end of G_1 to earth via the resistance K_1 but the resistance K_1 is by-passed so long as switch F_1 is closed so that the closure of switch J_1 has no immediate effect. This state is maintained until time 7 at which time terminal 7 is earthed momentarily, winding B_1 is de-energised, and switches D_1 and F_1 are opened. The reason for arranging that the switches D_1 and F_1 are opened at time 7 will appear subsequently. Relay winding B_1 thereafter remains de-energised until time 1 in the next cycle of operation. The opening of switch F_1 does not however, de-energise the winding G_1 since current can now flow from the terminal 18 through the alternative path provided by switch J_1 resistance K_1 and the switch N to the earth bar H . The resistance K_1 is arranged to have substantially the same magnitude as the resistance of winding G_1 and therefore the opening of the switch F_1 although it does not de-energise winding G_1 , has the effect of halving the current through the winding G_1 . The situation thus attained is maintained until time 18 when the terminal 18 is earthed, de-energising the winding G_1 and thereby opening the switches A_1 and J_1 . Nominally at the same time, the store S_{10} of the preceding inductive section L_{10} is cleared. It is arranged that this clearance is effected by de-energization

of a series of relays having a winding of the same resistances as the winding G_1 but not, however, associated with a series resistance such as K_1 so that it carries double the current of the winding G_1 just prior to time 18. 5 This has the effect of causing the switch A_1 to open just before the store S_{10} is cleared so that there is no risk of the section L_{10} being coupled into the potentiometer after its store has been cleared. When the store S_1 is filled at time 1 the fact that two relays have to operate before switch A_1 is closed, whereas only single relays have to operate to fill the store S_1 ensures that the store is filled just before the switch A_1 is closed.

During this progressive linking of the sections L_1 , L_2 to L_{10} the system has a weighting period less than 9τ , the weighting period being in fact equal to the number of switches A_1 , A_2 etc. which has been closed. There is thus no need to introduce any external control to ensure that the system settles in the shortest possible times.

If the acceleration of the magnitude x is large the output of the amplifier Q will increase due to the inevitable time lag in the servo loop, and when the amplifier output exceeds the aforesaid low value relay P operates to change the state of switch N and connect K_1 to the 18 volt bias source. When the switch N is in this condition the opening of the switch F_1 at time 7 (as above described) has also the effect of opening the switches A_1 and J_1 since no potential difference exists at the relevant time across G_1 and K_1 in series. This means that the switch A_1 remains closed only from time 1 to time 7, that is for a period of 3τ , and similarly each of the succeeding switches A_2 , etc., remains closed for the same reduced period. In this way the weighting period of the apparatus is automatically reduced from 9τ to 3τ in dependence upon the output of the amplifier Q which in turn is dependent upon accelerations of the quantity x . The form of the weighting function is, moreover, accurately maintained even when the weighting period is reduced.

The servo-system Q , U , V , W , is illustrated merely to show one method whereby the switch N can be operated in dependence upon acceleration of x . Other means are available, for example the switch N may be arranged for operation in dependence upon information as to the currents in the feed resistances R_1 . . . R_{10} .

Alternately if x represents for instance the magnitude of one Cartesian component of the position of an object such as a ship or an aeroplane, and apparatus precisely similar to that described herein is provided for measuring the rate of change of another Cartesian component y , then the course angle C of the object's motion, which is equal to the inverse tangent of y divided by x , may be obtained, for instance by means described in United States application Serial No. 207,728, now Patent No. 2,781,967. The rate of change c of C may be measured by means similar to those described herein and a large value of c may be used to operate switch N .

What we claim is:

1. A potentiometer comprising an array of impedances, 60 a switch between each impedance of said array and the next impedance thereof and between the last impedance of said array and the first impedance thereof, each switch being arranged when closed to connect adjacent impedances, means for feeding electrical signals to fixed points in the respective impedances, and means for operating said switches in a cyclic order to connect a cyclically changing plurality of said impedances in a series chain, said cyclic order being predetermined to produce the effect of displacing the feed points in succession along the chain.

2. Apparatus for evaluating the rate of change of a first variable with respect to a second variable comprising an array of inductances magnetically coupled one to another, a switch between each inductance of said array and the next inductance thereof and between the last

inductance of said array and the first inductance thereof, each switch when closed being arranged to connect the adjacent inductances, a plurality of impedances one leading to a fixed point on each inductance, means for operating said switches in a cyclic order to connect a cyclically changing plurality of said inductances in a series chain, the cyclic order being predetermined to produce the effect of displacing said fixed points in succession along said chain, and means for applying to said impedances alternating voltages representative of values of the first variable corresponding to values of the second variable represented by said points, the impedance and mutual coupling of said inductances being such that the potential gradient set up along the chain is representative of a smoothed rate of change of the first variable with respect to the second variable.

3. Apparatus according to claim 2 including means for modifying the cyclic operation of said switches so as to reduce the number of inductances connected in the series chain, thereby to reduce the interval over which the smoothed rate of change of the first variable is evaluated.

4. Apparatus according to claim 3 wherein the means

for operating each switch includes a main relay, means for maintaining said main relay energised during part of each cycle of operation of said switches, an auxiliary relay arranged to be energised when the main relay is energised and associated with hold means for maintaining said auxiliary relay energised for a longer part of each cycle, said auxiliary relay being arranged to operate the respective switch and said means for modifying the cyclic operation of the switches comprises means for rendering the hold means for each auxiliary relay inoperative.

5. Apparatus according to claim 3 comprising means responsive to a variation in the rate of change of the first variable for rendering said means for modifying the cyclic operation of the switches automatically effective when the rate of said variation exceeds a predetermined value.
